Application November 20, 1937, Serial No. 175,616

25 Claims.

(Cl. 93—3)

This invention relates to packet making and filling machinery.

The invention has for an object to provide a novel construction of machine adapted to form envelope-like packets from sheet material, more especially from metallic foil, and thereupon fill the same with material to be enclosed thereby. Another object of the invention is to provide a fully automatic and high speed machine for the purposes stated.

A further object of this invention is to provide means for moving the material from which the packet is formed intermittently and progressively, step by step, while subjecting the same to successive forming and filling operations, and whereby the discharge of the complete packets in continuous succession from the machine is attained.

Other objects of this invention, not at this time more particularly enumerated, will be comprehended in the following detailed description of the invention.

An illustrative embodiment of the invention is shown in the accompanying drawings, in which:

Fig. 1 is a front elevation of the machine, and Fig. 2 is a right hand end elevation of the same, certain parts being omitted in the latter view.

Fig. 3 is a vertical sectional view of portions of the machine, the same being taken on line 3—3 in Fig. 1.

Fig. 4 is a detail transverse vertical section, taken on line 4—4 in Fig. 2, but drawn on an enlarged scale, the same showing certain folding mechanism operative in forming the packets; and Figs. 5 and 6 are fragmentary views showing operations of the folding mechanism, these latter views being drawn on a still larger scale.

Fig. 7 is a sectional view through a packet as formed by the initial side folding operations; and Fig. 8 is a similar view of the packet as formed by the final side folding operations.

Fig. 9 is a face view of a packet as formed prior to filling the same.

Fig. 10 is a fragmentary transverse vertical section, taken on line 10—10 in Fig. 3, but drawn on an enlarged scale.

Fig. 11 is a fragmentary detail plan view of the conveyer means for progressively moving the initially formed packets subject to filling and closing operations, and certain other optional operations, and finally to the point of discharge from the machine; and Fig. 12 is a similar view showing another operative position of said conveyer means.

Fig. 13 is a fragmentary vertical cross section showing the mechanism for filling the packets,

said view being taken on line 13—13 in Fig. 1, but drawn on an enlarged scale; and Fig. 14 is a similar fragmentary view showing the filling mechanism as positioned to perform the filling operation.

Fig. 15 is a fragmentary vertical cross section showing end folding mechanism for closing the filled packet, said view being taken on line 15—15 in Fig. 1, but drawn on an enlarged scale.

Fig. 16 shows a sectional view of the filled and closed packet; and Fig. 17 shows a face view of the same, with a face wall thereof provided with perforations which are sometimes desired in connection with special uses to which the filled packets may be put.

Similar characters of reference are employed in the above described views, to indicate corresponding parts.

The various cooperating mechanisms making up the machine according to this invention are mounted upon a horizontal bed-plate 20; said bed-plate in turn being supported by a suitable leg frame structure (not shown).

Supported from said bed-plate 20, by standards 21, is a pair of transversely extending spaced frame bars 22 in connection with which is mounted the mechanism operative to form the packets which are to be subsequently filled and closed. Supported from said bed-plate 20, by standards 23, is another pair of longitudinally extending spaced frame bars 24, in connection with which is mounted a suitable runway structure (to be subsequently described) to which the formed packets are delivered from the packet forming mechanism, and along which said packets are moved subject to filling, closing and other operations which may optionally be desired to be performed in connection therewith.

The means for forming the packets comprises the following mechanism:

Journalized in and between the frame bars 22, respectively adjacent the opposite ends thereof, are rotatable shafts 25 and 26. Fixed on these shafts 25 and 26, in laterally spaced apart relation, are sprocket wheels 27 over which run laterally spaced conveyer chains 28. Affixed to said frame bars 22, to extend transversely therebetween and intermediate the running courses of said conveyer chains 28, are upper and lower cross bars 29. Supported by the upper cross bars, so as to extend longitudinally parallel and adjacent to the forwardly moving courses of said conveyer chains 28, are upper channeled guide bars 30, and, in like manner, supported by the lower cross bars, so as to extend longitudinally parallel 35

and adjacent to the return courses of said conveyer chains 28, are lower channeled guide bars 31. Affixed to and extending transversely between the conveyer chains, at longitudinally spaced intervals in connection therewith, are carrier members 32. These carrier members 32 are provided at their outer extremities with traction rollers 33, which travel in and through the channels of said guide bars 31. Supported from 10 the upper cross bars 29, by uprights 34, to extend longitudinally, intermediately, and somewhat above the forwardly moving courses of said conveyer chains 28, is a table plate 35. Said carrier members 32 are suitably formed to provide 15 upwardly extending portions 36 adapted to straddle said table plate 35. Affixed to said portions 36 of the carrier members 32 are forwardly projecting and horizontally disposed push-plates 37 adapted to be moved along the upper surface 20 of said table plate 35 by the operation of said conveyer chains 28. Said push-plates 37 are provided with chamfered marginal side portions 38. Suitably supported to extend in outwardly spaced relation to the side margins of said table 25 plate 35, and outwardly of the upwardly extending portions 36 of said carrier members 32, are fixed fold-backing rails 39.

Means is provided for driving the conveyer chains 28, and the devices carried thereby as 30 above described, with an intermittent progressive movement. To this end a drive shaft 40 is journaled in suitable bearings 41 mounted upon the bed-plate 20. Said drive shaft 40 is driven from a suitable source of power (not 35 shown) by a transmission chain 42, or other equivalent power transmitting means, which actuates a drive sprocket 43 adapted to be connected and disconnected, at will, with said shaft 40 through the agency of a suitable manipulatable clutch mechanism 44. Said drive shaft 40, in turn, drives a counter shaft 45, which is disposed at right angles thereto, through the interengaged bevel gears 46 and 47. Said counter shaft 45 is journaled in suitable bearings 48 mounted upon said bed-plate 20. From said 45 counter shaft 45, the shaft 25 of the sprocket chain conveyer mechanism is driven by a suitably designed Geneva gear transmission means 49, whereby the desired intermittent movement 50 of said sprocket chain conveyer mechanism is attained.

Disposed adjacent to the rearward end of said table plate 35 is the means for supplying the material from which the packets are to be 55 formed. Supported from the frame bars 22 by posts 50 are side frames 51. Mounted upon a shaft 52, which is journaled in and between the upper ends of said side frames 51, is a guide roller 53. Journaled in and between said side frames 51 below said guide roller 53 is a shaft 54 upon which is mounted one feed roller 55 of a pair thereof, the other feed roller 56 of said pair being fixed on a parallel shaft 57 which is mounted in bearings movably supported by said 60 side frames 51, so as to be urged by spring means 58 in such manner as to yieldably press the roller 56 toward and in engagement with the roller 55. The means for driving said feed rollers 55-56 comprises a chain and sprocket transmission 59 70 between said counter shaft 45 and said shaft 52. Fixed on said shaft 53 is an intermittent drive gear 60. The shaft 54 and feed roller 55 thereon is driven by said intermittent drive gear 60 through intermediate gearing 61 in such manner as to produce a desired properly timed in-

termittent operation of said feed rollers. Feed roller 56 is driven from and in an opposite direction to feed roller 55 by gearing 62 between shafts 54 and 57.

Upstanding from the bed-plate 20 is a stand- 5 ard 63, which supports a spindle 64 for rotatably mounting a reel 65 adapted to carry a supply roll 66 of the sheet material from which the packets are to be made. In the instant case, the sheet material consists of metallic foil, although 10 other kinds of sheet material may be employed accordingly as is best suited to the particular uses to which the formed packets are to be put. Cooperating with said reel 65 is a spring tensioned swinging frame 67, carrying guide rollers 15 68 over which the sheet material passes from the roll 66 to the guide roller 53; this arrangement operates to prevent both the formation of uncontrolled slack in the web of sheet material drawn from the roll thereof, as well as too free 20 rotation of said roll under the pull of said web.

The web of packet making material is led from the supply roll 66 over the guide rollers 68 and thence over the guide roller 53. From said guide roller 53, the web passes downwardly between 25 fixed guide plates 69 to the feed rollers 55-56, the same passing between the latter so as to be nipped thereby. The intermittent operation of said feed rollers 55-56 feeds downwardly the free end portion of the web, so that the latter 30 passes between the fixed blade 70 and the pivoted movable blade 71 of a cutting mechanism, thereupon passing downwardly between additional guide plates 72, which extend below said cutting blades, and which terminate somewhat be- 35 hind and slightly above the rearward end of the table plate 35.

Disposed in vertical alignment below the guide plates 72 is a vertically oscillatable guide means comprising guide plates 73. The forward guide plate 73 is provided with tensionally yieldable lip piece 74 which projects above the plane of the upper margins of said guide plates 73. Said guide plates 73 are supported by an oscillatable arm 75 which is pivoted on a fulcrum shaft 76 supported by and extending between the frame bars 22. The pivoted end of said arm 75 is provided with a downwardly projecting actuating arm 77. A cam means 78 mounted on the counter shaft 45 operates through the connecting link 79, the outer end of which is pivotally engaged with said actuating arm 77, to produce suitably timed oscillatory movements of said guide means comprising said guide plates 73.

The means for producing properly timed operation of the movable blade 71 of the cutting mechanism (see Fig. 2) comprises an actuating lever 80 fulcrumed intermediate its ends by a pivot stud 81. The lower arm of said actuating lever 80 is operatively connected, in any suitable manner, to the free end of the movable blade 71 of the cutting mechanism. The upper arm of said actuating lever 80 is provided with an anti-friction roller 82 which is operatively engaged by a cam 83 mounted on the shaft 52. This cam 83 85 serves to produce suitably timed oscillation of said actuating lever 80, whereby timed movements of said movable cutting blade 71 relative to the fixed cutting blade 70 are in turn produced.

A horizontally oscillatable web gripper means (see Fig. 3) is provided to cooperate with the yieldable lip piece 74 of said oscillatable guide means, the same comprising a forwardly projecting gripper plate 84 carried upon the depending 75

arm 85 of a spring tensioned lever means fulcrumed by a pivot stud 86 upon one of the side frames 51. The opposite arm 87 of said lever means is provided with an anti-friction roller 88 which is operatively engaged by a cam 89 mounted on the shaft 52. Said cam 89 serves to produce suitably timed oscillation of said lever means and the gripper plate 84 carried thereby. The forwardly projecting free end portions of the push-plates 37, which are actuated by the above described conveyer mechanism, are centrally cut away to provide clearance for accommodation of the gripper plate movements, which occur as the push-plates successively approach the rearward end of said table plate 35.

The feeding of the web of material from the supply thereof for delivery to the packet forming mechanism is carried on as follows:

Timed operation of the feed rollers 55-56 draws the web from the supply roll 66, and feeds down the free end portion thereof a predetermined distance below the cutting blades 70-71. The thus down-fed free end portion of the web passes between the guide plates 72, and thence between the guides plates 73 of the oscillatable guide means; the latter means being in an operative upraised position (as shown in Fig. 3) during the descending movement of said web end portion. The down-fed web portion is disposed, by the described feeding movement thereof, perpendicularly across the rearward end of the table plate 35 and in front of an approaching push-plate 37, the timed movement of which is controlled by the operation of the intermittently actuated conveyer chain mechanism. As soon as the down feeding movement of the web end portion is completed, the gripper plate means is, by its actuation, operated to advance the gripper plate 84, so that the free end thereof engages the down-fed web portion in such manner as to grip the same between said gripper plate end and the tensionally yieldable lip piece 74, thus holding the same in properly positioned relation to the approaching push-plate 37, and against displacement from such position when said down-fed end portion is severed from the main body of the web by the action of the cutting mechanism. While the down-fed web portion is thus held, the cutting mechanism is timed to so function that the movable blade 71 is swung relative to the fixed blade 70 to shear through the web and thus sever therefrom a portion of properly predetermined length according to the size of packet to be formed therefrom.

Subsequent to the web severing operation, and while the severed portion, which now constitutes a packet blank, is still gripped between the gripper plate 84 and lip-piece 74, the approaching push-plate 37 is advanced so that its free end engages the blank so as to grip the same between said push-plate end and said lip-piece, upon which occurrence the timed actuation of the gripper plate means operates to retract said gripper plate 84 to normal initial position. Continued advance of the blank engaging push-plate 37 operates to advance the blank with transverse folding effect thereupon, so that the lower portion is upfolded against the bottom of said push-plate, as the latter moves over the rearward end of the table plate 35, while the upper portion of the blank is downfolded upon the top of said push-plate, as the latter moves beyond the lower margin of the forward guide plate 72. As these operations are initiated, the

timed actuation of the oscillatable guide means operates to downwardly retract the guide plates 73 so that the push-plate structure may pass thereover, whereafter the guide-plates 73 are again returned to normal upraised position.

The blanks as folded over the push-plates in the manner above described are thereupon intermittently advanced along the table-plate 35, with their free lateral marginal portions overlying the fold-backing rails 39, subject to the operation of side fold or seaming mechanisms which constitute operative parts of the packet forming mechanism.

In the packet forming operations, the superposed side marginal portions of the initially folded blank are seamed by means of inturned double lap folds. These lap folds are formed by folding mechanisms successively located at two stations bordering the table plate 35; the first folding mechanism operating to make the first lap fold, and the second folding mechanism operating to make the second lap fold, all whereby the desired double lap seam is formed. These respective first and second folding mechanisms are substantially the same in construction and mode of operation, and are actuated, in properly timed relation to the intermittent advance of the packet blanks along the table plate 35, by common actuating and timing means.

The folding mechanisms each comprise the following construction:

Journalized in spaced apart bearing bracket members 90, pairs of which are respectively affixed to the respective frame bars 22, are rock-shafts 91 which are respectively disposed in upwardly and outwardly offset relation to the respective adjacent sides of the table plate 35 and to the fold backing rails 39 associated therewith. Loosely pivoted upon each rock-shaft 91, as a fulcrum, is a vertically oscillatable arm 92 upon the free end of which is secured an anvil plate 93, the latter substantially corresponding in width to the length of the initially folded packet blanks. Said anvil plate 93 is preferably provided with a chamfered lower free edge portion 94. Fixed on each rock-shaft 91 is a folder arm 95, which normally inclines downwardly toward the adjacent fold backing rail 39. Pivotedly connected with and carried by the free end portion of said folder arm 95 is a folder block 96, the latter normally occupying a substantially right angular upturned relation to the longitudinal axis of said folder arm 95, being yieldably held in such position by spring means 97 which urges the same into engagement with an adjustable stop screw 98 carried by a laterally offset lug 99 with which said folder arm 95 is provided. Connected with said folder block 96, in outwardly offset but substantially parallel relation to the outer or lower face thereof, is a folder blade 100, the same preferably having a chamfered upper free edge portion 101. Pivotedly connected by its lower end portion, by means of a pivot pin 102, with the free end portion of said folder block 96 is a link 103. This link is provided at its upper end portion with a slot 104 of predetermined length. This slot 104 engages over a stationary stop stud 105 which is suitably supported from the adjacent bracket member 90, as e. g. by means of an extension 70 piece 106 connected with the latter.

In order to attain simultaneous timed operation of the opposed folder mechanisms of each set thereof, as well as actuation of both sets of folder mechanisms from and by a common ac-

tuating means, the anvil arms of the first and second sets common to respective sides of the table plate 35 are connected or coupled together by suitable cross-head means 107, and the opposite cross-head means are interconnected by a link element 108 which is pivotally connected to and between knuckle members 109 and 110 with which the respective cross-head means are provided; similarly the folder arms 95 of the first and second sets common to respective sides of the table plate 35 are affixed to a rock-shaft 91 common thereto, the opposite rock-shafts 91 being interconnected by a link element 111 which is pivotally connected to and between crank-arms 112 and 113 with which said respective rock-shafts are provided.

The means for producing properly timed operation of the described folder mechanisms comprises anvil operating means and folder operating means (see Figs. 2 and 4). The anvil operating means comprises a suitable cam member 114 which is mounted on and actuated by the drive shaft 40. This cam member 114 cooperates with the forked end plate 115 of a connecting rod 116 so as to produce timed reciprocation of the latter. Said connecting rod 116 is pivotally connected by its upper end with a lever arm 117 with which the cross head means 107, connecting the anvil arms at the adjacent side of the folder mechanisms, is provided. The folder operating means comprises a similar suitable cam member 118 which is also mounted on and actuated by said drive shaft 40. Said cam member 118 cooperates with the forked end plate 119 of a connecting rod 120 so as to produce timed reciprocation thereof. Said connecting rod 120 is pivotally connected by its upper end with a lever arm 121 suitably affixed to the rock-shaft 91 at the adjacent side of the folder mechanisms.

40 In operation, the folder mechanisms function as follows:

As an intermittently advanced push-plate 37 moves the packet blank carried thereby between the folder mechanisms of the first set thereof it comes to rest so that the packet blank dwells between said folder mechanisms subject to the operation of the latter thereon. The superposed lateral marginal portions of the packet blank are initially disposed in overlying relation to the fold-backing rails 39, and so that portions thereof project outwardly beyond the latter; these outwardly projecting lateral portions of the packet blank being thus initially disposed intermediate the upraised anvil plates 93 and the lowered folder blades 100. As the packet blank comes to rest, the timed actuation of the anvil plate arms 92 operates to swing the anvil plates 93 downwardly so that the free edge portions 94 thereof engage said protecting lateral portions of the packet blank adjacent to the outer margins of the underlying fold-backing rails 39 (see Fig. 4). Subsequent to the described lowering of the anvil plates 93, the timed actuation of the folder arms 95 operates to swing the folder blades 100 upwardly. The initial upward movement of the folder arms 95 causes the folder blades 100 to engage the undersides of the projecting lateral portions of the packet blank and thereupon uplift, upturn and partially infold the same around the edges 94 of the anvil plates 93 (see Fig. 5). During this initial upward movement of the folder blades 100, the links 103 connected with the folder blocks 96 are also caused to move upwardly, the slots 104 thereof riding along the stop studs 105. By the time the partial infolding of

the lateral portions of the packet blank is completed, the lower ends of the slots 104 of links 103 abut the stop studs 105, thus arresting any further upward movement of said links (see Fig. 5). As this occurs, the timed actuation of the anvil plate arms 92 operates to upwardly retract the anvil plates 93 to normal initial positions, thus withdrawing the latter from beneath the partially infolded lateral portions of the packet blank. In the meantime, the actuation of the folder arms 95 continues the upswinging movement thereof. Since, however, the links 103 are arrested as above described, the continued upswinging movement of said folder arms 95 causes the latter to thrust against the ends of the folder blocks 96 which are pivotally connected therewith, but since the opposite ends of these folder blocks, which are pivotally connected to the arrested links 103, cannot move further upward, the thrust of said folder arms 95 operates to turn the folder blocks 96 about the pivotal connections 102 thereof with said links 103 and against the tension of the springs 97. The turning of the folder blocks 96, thus induced, operates to swing downwardly the folder blades 100 with the effect that the partially infolded lateral portions of the packet blank are completely infolded and pressed flatly downward against the blank body as supported by the underlying fold-backing rails 39 (see Fig. 6). After completion of this operation, the timed actuation of the folder arms 95 operates to retract the same to down-swung normal initial positions and to return the folder devices connected therewith likewise to their normal initial positions. The above described operations are performed by the first set of folder mechanisms at one station, thereby producing the first or single fold of the packet side seams, as shown at A in Fig. 7. For some types of packets such single fold side seam may be all that is required or desired, in which case the packet thus formed may be passed on for filling and closing without submission to the operation of a second set of folder mechanisms. In the illustrative embodiment of the machine according to this invention, the folding or seam forming means includes a second set of folder mechanisms. Upon completion of the first or single fold of the packet side seams, the intermittent operation of the push-plate conveyer mechanism advances the packet blank to a succeeding station, where the same is brought to rest in position to be operated upon by said second set of folder mechanisms. Said second set of folder mechanisms is constructed and operates in the same manner as the above described first set of folder mechanisms, but is so adjusted to the packet blank carrying and supporting means as to function to again fold the first or single fold upon itself, thus producing the final double fold packet side seams, as shown at B in Figs. 8, 9 and 17.

It will be understood that should it be desired to adhere the seam forming laps together, any suitable adhesive substance may be applied to the laps to so adhere the same together as they are formed.

Upon conversion of the packet blank into an envelope-like packet by the formation of the above described packet side seams, the push-plates 37 carry the same on to the forward end of the conveyer mechanism, and beyond the forward end of the table plate 35, adjacent to which is located means for removing the packets from said push-plates 37 and thereupon transferring the same to the receiving end of a runway struc- 75

ture along which the packets are moved subject to filling, closing and, if desired, other operations as will hereinafter appear.

The means for stripping the packets from the push-plates 37 and for moving the same to a transfer means comprises the following mechanism (see Figs. 1, 2, 3 and 10):

Provided in connection with certain of the bearing bracket members 90, located at the far ends of the packet side seam folder mechanisms, are upstanding bearing blocks 122. Journaled in and between said bearing blocks 122 is a transverse rock-shaft 123. Fixed on said rock-shaft 123 are a pair of laterally spaced forwardly projecting slotted guide arms 124, the same being subject to timed vertical oscillation by the operative movements of said rock-shaft. Guided by said guide arms 124 for forward and backward reciprocation, and also so as to be moved, at proper times, up and down by the vertical oscillation of said guide arms, is a carriage means comprising a body member 125 which is disposed between said guide arms. Said body member 125 is provided with laterally and oppositely projecting guide studs or tongues 126 which are slidably engaged in the slots of said guide arms 124. Affixed to the bottom end of said body member 125 is a bottom plate 127, and affixed to the upper end of said body member is a top plate 128. Affixed to and extending vertically between said bottom plate 127 and top plate 128, one in front and one behind said body member 125, are guide rods 129. Suitably affixed to the rearward end portion of said bottom plate 127 is a downwardly projecting stripper member 130. Similarly, suitably affixed to the forward end portion of said bottom plate 127 is a downwardly projecting propulsion member 131. Means are provided for imparting to said carriage means properly timed forward and backward movements, the same comprising a reciprocable slide plate 132 which is movable between guide rails 133 of a horizontal track plate 134, the latter being supported in connection with one of the frame bars 45 adjacent to one side of the path of reciprocation of said carriage means. Secured to and upstanding from said slide plate 132 is a post 135 from which extends a laterally projecting coupling bar 136, through the free end portions 137 of which the vertical guide rods 129 of said carriage means are slidably engaged. By this arrangement forward and backward reciprocation of said slide plate 132 is transmitted to said carriage means while at the same time permitting 55 vertical up and down movements of the latter for purposes presently to be made known. The timed reciprocation of said slide plate 132 is produced by a suitable cam member 138 mounted on and rotated by said counter-shaft 45. Said cam member cooperates with and actuates a pivoted lever member 139, the movements of which are transmitted to said slide plate 132 by the interconnecting link 140. The timed actuation of the 60 rock-shaft 123, whereby vertical oscillation of said guide arms 124 and the carriage means supported thereby is produced, is effected by means of another suitable cam member 141 which is also mounted on and rotated by said counter-shaft 45. Said cam member 141 cooperates with the forked end plate 142 of a connecting rod 143. Said connecting rod 143 is pivotally connected by its upper end with a lever arm 144 suitably affixed to the rock-shaft 123.

75 Beyond and spaced from the forward end of

the table plate 35 is a packet receiving platform 145, the same being supported by a base piece 146 affixed to the inner of the two frame bars 24. Preferably the top surface of said platform 145 is provided with longitudinally extending laterally spaced ribs 147, with which dovetail corresponding projections 148 with which the lower margin of the propulsion member 131 carried by said carriage means is provided. By this intermeshing relation of said propulsion member 131 and said platform top, a packet engaged by the former cannot be improperly engaged, and all risk of any portion thereof being caught or interposed between the moving propulsion member and the stationary platform is entirely 15 obviated.

The operation of the above described stripping and transfer mechanism is as follows:

As a push-plate 37 carrying a packet reaches the end of its forward movement, and just prior 20 to being carried downwardly around the forward sprocket wheels 27 for return to the rearward end of the table plate 35 by the returning courses of the conveyer chains 28, the dwell thereof in such position holds the packet carried thereby 25 subject to the operation of stripping the same therefrom. By the time the push plate 37 and packet thereon have been thus positioned, the carriage means has been moved to retracted position, so that downward swinging movement of the guide 30 arms 124 lowers the carriage means to thereby dispose the stripper member 130 behind the rearward end of the packet carried by the dwelling push-plate 37. Upon this occurrence forward swinging movement of the lever member 139 is 35 induced by cam member 138 which operates to move forward the slide plate 132 and, through the described connections, thus produce a forward movement of the carriage means relative to the lowered slotted guide arms 124, which, in turn, 40 causes the stripper member 130 to push forward the packet relative to the stationary push-plate 37, thereby stripping said packet away from said push-plate and thereupon delivering the same upon the platform 145. Upon completion of 45 this operation, the conveyer chains 28 again take up their movement, whereby the push-plate 37, from which the packet has been thus removed, is caused to swing down around the forward end of the table plate 35 for return to the rearward 50 end of the latter, while simultaneously a succeeding push-plate 37, and the packet carried thereby, is moved forward into position to have the packet stripped therefrom. While this is occurring, the cam member 141, through the connecting rod 143 and lever arm 144, operates to rock the rock-shaft 123 in clockwise direction to swing upwardly the slotted guide arms 124, thereby uplifting the carriage means and stripper member 130. While the carriage means and stripper member 130 are thus uplifted, the timing operation of cam member 138 causes the lever arm 139 to swing back to normal initial position, and through the described connections therewith, causes the carriage member and stripper member 130 to move backward over said succeeding push-plate 37 and packet thereon, following which the timing operation of cam member 141 operates to rock said rock-shaft 123 in anti-clockwise direction to again swing downward said slotted guide 70 arms 124, and thus again lower the carriage means to operative position with the stripper member disposed behind and ready to engage said succeeding packet, whereupon the above described operations are repeated. As said succeeding packet 75

is engaged and stripped from the push-plate carrying the same, the previously removed packet which rests upon the platform 145 is engaged by the propulsion member 131, which has been lowered behind the same by the downward movement of the carriage means, so that, as the carriage means is again moved forward this packet is pushed off of the platform 145 and into a transfer means by which it is upturned and deposited in position to enter and be propelled in a runway subject to filling, closing and perhaps other desired operations.

The transfer means referred to comprises a bearing bracket 149 which is affixed to one of the frame bars 24, and journaled in said bearing bracket is a rock-shaft 150 upon which is mounted an oscillatable arm 151 which is provided with a laterally offset slotted receiver 152. Timed operation of said arm and its receiver is produced by the following actuating means. Suitably pivoted in connection with bed-plate 20 is an oscillatable lever member 153, the timed movements of which are controlled by a suitable cam member 154 mounted upon and actuated by the countershaft 45. Pivotedly connected with the free end portion of said lever member 153 is a connecting rod 155, the opposite end of which is pivotally connected in turn to the free end of a lever arm 156 which is affixed to said rock-shaft 150. In operation, preparatory to the discharge of a packet from the platform 145 by the operation of the propulsion member 131 above described, the slotted receiver 152 is disposed in horizontally aligned position relative to said platform 145, so that the packet, as propelled by the actuated propulsion member 131, is pushed into the slot of said receiver 152. After this packet is thus engaged in said receiver 152, timed operation of the latter by the described means for actuating the same, upturns the same from said horizontal position to a vertical position, whereby the packet carried thereby is disposed in an upstanding position at the receiving end of a runway structure and subject to the operation of a combined oscillatory and reciprocatory transport means accordingly as now about to be described.

As will be observed by inspection of the accompanying drawings, the longitudinally extending frame bars 24 extend at right angles to the frame bars 22 upon which the described packet forming mechanism is mounted. Mounted in connection with the outermost frame bar 24, by supporting posts, is a runway platform 157, and affixed to the latter are outer and inner bottom guide plates 158 and 159, the opposed margins of which are spaced apart to form a guide channel to receive the bottom end of the packets, when the latter are deposited in upstanding position upon the runway platform 157. Suitably suspended from bracket structures 160, which spring from the other frame bar 24, are outer and inner guide rails 161 and 162, the same being spaced apart to provide an intermediate guide space through which the upper end portions of the upstanding packets move. Said runway platform, guide plates and guide rails constitute a vertical packet runway structure which extends to a point just beyond a station at which is located a packet closing mechanism subsequently to be described. Beyond such termination of said vertical packet runway structure extends a horizontal packet runway structure, the same comprising a continuation runway platform 163 provided with spaced side rails 164 and 165, the whole forming a runway channel of a width sufficient to receive

and permit movement therethrough of the packets when the latter are upset from upstanding position to a horizontal or flat lying position.

The oscillatory and reciprocable transport means by which the packets are successively and progressively moved intermittently or step by step through said respective vertical and horizontal packet runway structures comprises (see Figs. 1, 2, 11, and 12) a longitudinal pivot shaft 166 journaled in bearing standards 167 which are mounted on the bed-plate 20 and on an extension bracket 168 connected with the latter. Affixed to said pivot shaft 166, in longitudinally spaced relation, are upwardly extending rocker members 169, to the upper free ends of which is secured a longitudinally disposed base bar structure 170. Said rocker members and base bar structure constitute a transport carrier adapted to swing in and out laterally, i. e., at right angles to the path of movement of packets through the runway structures. Pivotedly connected with said base bar structure 170, to extend horizontally inward therefrom, are a plurality of longitudinally spaced carrier arms 171. Pivotedly attached to the free ends of carrier arms 171 is a longitudinally extending transport bar 172, the same having a plurality of suitably spaced impeller members 173 projecting laterally therefrom. Pivotedly connected with said carrier arms 171, intermediate the ends thereof, is a reciprocator bar structure 174, longitudinal reciprocation of which operates to swing forward and backward said carrier arms, to thereby produce longitudinal reciprocation of said transport bar 172 in the direction of the path of movement of packets through the runway structures.

The means for laterally oscillating the transport carrier is operated from a counter shaft 175 which is journaled in bearings 176, and which is driven from said drive shaft 40 by the interconnecting bevel gearing 46-177. Fixed on and driven by said counter shaft 175 is a cam member 178 which serves to effect properly timed actuation of a pivoted transversely oscillatable lever means 179, the upper free end portion of which is interconnected by a link 180 with one of said rocker members 169 of the transport carrier.

The means for producing properly timed reciprocation of said transport bar 172 through said reciprocator bar structure 174 comprises a transverse rock-shaft 181 journaled in and between the pair of standards 23 adjacent the receiving end of the runway structure. Affixed to one end of said rock-shaft 181 is a crank-arm 182. Mounted on and driven by said drive shaft 40 is a suitable cam member 183. Said cam member 183 cooperates with the forked end plate 184 of a connecting rod 185, the free end of the latter being pivotally connected with said crank-arm 182. Affixed to the other end of said rock-shaft 181 is an upwardly extending lever member 186, to the free end of which is coupled, by a universal knuckle connection 187 one end of a connecting rod 188. The opposite end of said connecting rod 188 is connected, by a like universal knuckle connection 189, to said reciprocator bar structure 174. If desired an anchored spring member 190 may be connected to said lever member 186 to assist the forward thrusting movement thereof and to prevent undesired play or back-lash.

In operation, after the transfer receiver 152 is upturned to deposit a packet upon the runway platform 157 in upstanding position adjacent to the entrance of the above described vertical packet runway structure, the transport carrier,

with the transport bar 172 retracted to normal initial position, is timed by its actuating means to swing inwardly, thus disposing the rearmost impeller member 173 behind said upstanding packet. 5 While the transport carrier dwells in its inwardly swung position, the means for actuating the reciprocator bar structure 174 is timed to produce a forward movement thereof in the direction of the arrow x (see Fig. 11). This forward movement of the reciprocator bar structure 174 swings forward the carrier arms 171, and thereby imparts a forward longitudinal movement to said transport bar 172, so that said rearmost impeller member 173 moves the packet one step forward and 10 into the receiving end of the vertical packet runway structure. It will also be understood that the several packets previously introduced into the runway structures will be likewise each advanced forwardly therethrough one step. Upon completion of the forward movement of the transport bar 172, the transport carrier is timed by its actuating means to swing outwardly in the direction of the arrow y (see Fig. 11) thus withdrawing the impeller members 173 of the transport bar 172 outwardly and away from the packets disposed in the various advanced positions within the runway structures, in which positions said packets dwell subject to the various operations desired to be performed with respect thereto, as will presently appear. While the transport carrier dwells in outwardly swung position, the means for actuating the reciprocator bar structure 174 is timed to produce a backward or retractive movement thereof in the direction of the arrow x' (see Fig. 12), which in turn swings rearward the carrier arms 171 and thus retracts the transport bar 172, the impeller members 173 of the latter being outwardly removed from and thus being adapted to by-pass the packets. After 20 the transport bar 172 is thus retracted, the means for actuating the transport carrier is timed to again swing the same inwardly in the direction of the arrow y' (see Fig. 12), and the transport mechanism is again ready to repeat its above 25 described operative cycle.

Suitably stationed relative to the vertical packet runway structure is means for filling the packet with material desired to be enclosed therein (see Figs. 1, 13 and 14). The means illustrated for this purpose is adapted to deliver into the packet interior a measured quantity of powdered or granular material. Supported by means of a standard 190 from one of the frame bars 24, and so as to overhang the path of movement of the packets in said vertical packet runway structure, is a magazine or hopper 191. At the bottom end of said hopper 191 is fixed a throat housing 192 having a cylindrical bore 193. Said throat housing is provided at its upper side 30 with an intake port 194 communicating between its bore and the interior of said hopper. Said throat housing is also provided at its underside with a discharge opening 195. Cooperating with and extending downwardly from said discharge opening 195 is a vertically reciprocable funnel means 196 having a laterally tapered free end portion formed by a forwardly and downwardly inclined back wall 197 and a rearwardly and downwardly inclined front wall 198. The funnel means is affixed to a carrier arm 199 which is, in turn, affixed to the vertically extending branch 200 of a bell-crank lever means, the pivotal shaft 201 of which is journaled in a bearing bracket 202 which rearwardly extends from the standard 35 190. Said bell-crank lever means is provided with a rearwardly extending horizontal branch 203. The lower end portion of the front wall of said funnel means terminates in a pivoted, outwardly swingable gate member 204 which cooperates with the stationary lower end portion 5 of said back wall 197. The free bottom marginal edge portions of both said back wall 197 and said gate member 204 are inwardly chamfered, as at 205, to present, when these parts are normally closed together, a sharp wedge-like terminal 10 means calculated to easily enter into the open mouth of a packet when the funnel means is operatively related to the latter in the manner presently to be described. Said gate member 204 has affixed thereto, to project from the outer face 15 thereof, an actuator tongue 206. Arranged to cooperate with said actuator tongue 206 is an adjustable stop element 207, the same being carried by a supporting bracket 208 which is affixed to said throat housing 192. Journaled in 20 bearing standards 209, which spring from the inner frame bar 24, is the shaft 210 of cylindrical measuring and discharge valve 211 which fits within the bore 193 of said throat housing. Formed in the cylindrical surface of said valve 25 211 are a series of circumferentially spaced measuring pockets 212.

The means for vertically reciprocating the funnel means is operated from the counter shaft 45. Fixed on and driven by said countershaft 45 30 35 is a cam member 213 which cooperates with the forked end plate 214 of a connecting rod 215, the upper end of the latter being pivotally connected with said horizontal branch 203 of said funnel actuating bell-crank means. Spring means 216, 35 suitably anchored by its lower end, has its upper end connected with said bell-crank means branch 203, and serves to hold said end plate 214 of the connecting rod 215 in operative relation to the actuating cam member 213. The 40 operative periphery of said cam member 213 is provided with a series of peripherally spaced agitator cam portions 213' for purposes to be set forth.

The means for actuating the measuring and 45 discharge valve 211 comprises a drive gear 217, mounted for rotatable oscillation in connection with a bearing standard 209. This drive gear 217 meshes with and drives a pinion 218 on the shaft 210 of said valve 211. Timed oscillation 50 of said drive gear 217 is produced by an eccentric member 219 which is mounted on and driven by said counter shaft 45. Interconnected between said eccentric member 219 and said drive gear 217 is a connecting rod 220.

In the operation of the packet filling means, 55 when, during the transport of a packet through the vertical packet runway structure, said packet comes to rest beneath the funnel means of said filling means, with the open mouth of said packet opposed to the latter, timed operation of said funnel means, by its described actuating means, causes the same to descend so that its closed free end enters into the packet mouth. Just before this descending movement of said funnel means 60 is completed, the actuator tongue 206 of the gate member 204 strikes the stop element 207 so as to be arrested thereby with the consequence that further descent of said funnel means exerts an uplifting effect upon said actuator tongue 206 65 which is translated into an outward swinging movement of said gate member 204. This outward swinging movement of said gate member not only opens the funnel means to the discharge 70 of material therethrough, but also serves to 75

somewhat laterally expand the mouth of the packet so as to assure easy descent of discharged material into the interior of the packet (see Fig. 14). After the funnel means has thus been 5 operatively related to the packet mouth, the measuring and discharge valve 211 is rotated in an anti-clockwise direction from its normal initial position, wherein its pockets 212 are upwardly directed for communication with the interior of the hopper 191, and so as to be charged 10 with the material supplied by the latter. This rotation of the valve 211 causes the pockets 212 to successively move into communication with the funnel means, so that the charges of material 15 carried thereby are successively dumped into the funnel. By this arrangement, the full quantity of material to be delivered into the packet is not dumped en masse but in successive portions, whereby tendency to choke up, either at the outlet 20 of the funnel means or within the packet interior, is avoided. To further guard against the choking or bridging of the powdered material at the restricted outlet of the funnel means or within the packet, said funnel means is subjected 25 to a vertically reciprocal agitation or vibration during the flow of material therethrough and into the packet. Such agitation or vibration is induced by the agitator cam portions 213' of a cam member 213 in a manner which will be obvious 30 from an inspection of Fig. 13 of the drawings. Upon completion of the packet filling operation, the valve 211 is returned to normal initial position, and the funnel means is returned to normal uplifted position by the timing operation of their 35 respective actuating means, whereupon the packet transport means again functions to move onward the filled packet and simultaneously position a succeeding empty packet ready for a repetition of the above described filling operations.

Suitably stationed relative to the vertical packet runway structure are folding mechanisms which are operative upon the open mouth of the packet to close the same by a double lap end closure seam (see Figs. 1 and 15). These folding 45 mechanisms are positioned respectively at successive stations at which the movement of the filled packets by the transport means is arrested. The first folding mechanism operates to make the first lap fold of the closure seam, and the 50 second folding mechanism operates to make the second or doubling lap fold to complete the closure seam. These respective first and second folding mechanisms are, comparatively, substantially 55 the same in construction and mode of operation, and are actuated, in properly timed relation to the intermittent advance of the filled packets along the vertical packet runway structure, by common actuating and timing means.

Said end closure seam folding mechanisms each 60 comprise the following construction:

Journaled in spaced bearing brackets 221, which spring from the innermost frame bar 24, is an anvil means actuating rock-shaft 222 and also 65 a folder means actuating rock-shaft 223. The anvil and folder means structures each comprise substantially the same detail elements as already described in connection with the packet side seam folding mechanisms, and the same function in 70 the same manner and in the same relatively cooperative relation as do the latter, with the exception that they are positioned to operate upon the packets as disposed in a vertical plane instead of the horizontal plane as was the case with respect 75 to said side seam folding mechanisms. This

being so, detail description of said end closure seam folding mechanisms would be largely repetition, and consequently it is deemed sufficient to identify the parts of said end closure seam folding mechanisms by the same reference characters which have been heretofore referred to corresponding parts of said side seam folding mechanisms.

The means for producing properly timed operation of anvil means of said end closure seam folding mechanisms comprises, a suitable cam member 224 which is mounted on and actuated by said countershaft 175. This cam member cooperates with the forked end plate 225 of a connecting rod 226 so as to produce timed reciprocation of the latter. Said connecting rod 226 is pivotally connected by its upper end with a lever arm 227 which is affixed to and extends rearwardly from said anvil means rock-shaft 222.

The means for producing properly timed operation of the folder means of said end closure seam folding mechanisms comprises a suitable cam member 228 which is also mounted on and actuated by said countershaft 175. Said cam member 228 cooperates with the forked end plate 229 of a connecting rod 230 so as to produce timed reciprocation thereof. Said connecting rod 230 is pivotally connected by its upper end with a lever arm 231 which is affixed to and extends rearwardly from said folder means rock-shaft 223.

At a station bordering said vertical packet runway structure intermediate the filling station and the first end fold seam folder station, means are provided for pressing or closing together the laterally expanded margins or lips of the filled packet mouth, this being done preparatory to producing the first fold of said end closure seam. This means comprises a packet mouth backing block 232 which is supported in connection with the inner runway guide rail 162. Fixed on and actuated by the adjacent end of said anvil means rock-shaft 222 is a presser member 233. In operation, as the filled packet comes to a stop in front of said backing block 232, said presser member 233 is timed, by the actuating movement of said rock-shaft 222, to swing inwardly and thereby press the expanded open mouth of the filled packet between the same and said backing block, thus flatly pressing and closing together the margins or lips of said packet mouth.

Supported by the runway guide rail 162, bordering the end closure seam folding stations, is a fold backing rail 234 (see Fig. 15). The superposed closed together marginal portions of the packet mouth are initially disposed in overlying relation to the front face of said backing rail 234, so that portions thereof project upwardly beyond the latter. The successive operations of the anvil and folder means of the respective folding mechanisms will function, as the packets are submitted thereto, to fold said marginal portions of the packet mouth so as to form the desired double fold packet and closure seam C (see Figs. 16 and 17), the folding operations of said anvil and folder means being carried out in the same manner as already above set forth in connection with the previously described formation of the packet side seams.

Upon completion of the closing of the filled packets, the same are transported to a succeeding station adjacent to which the vertical packet runway structure terminates and the horizontal packet runway structure begins. At this station is situated means for down-turning the upstand-

ing packets to the upset or flat lying position in which they are transported through said horizontal packet runway structure. The means for down-turning the packets comprises a depending 5 oscillatable kicker plate 235 which is fixed on, and which is actuated at properly timed intervals by, the anvil means rock-shaft 222. As the packet leaves the vertical packet runway structure, its closed upper end registers with the free 10 end of said kicker plate 235, whereupon the latter is swung outwardly to tip over the packet to flat-lying position upon the platform 163 at the entrance of the horizontal packet runway structure. Certain of the impeller members 173 of the trans- 15 port bar 172 are provided, at their forward edges, with depending push fingers 236, whereby the flat-lying packets may be engaged, upon operative forward movement of said transport bar 172, and progressively and intermittently moved 20 through said horizontal packet runway structure. At the point where the packet is upset to flat lying position suitable means (not shown) may be provided, if desired, which is operative to shift the upset packet into properly registered and 25 aligned relation to the horizontal packet runway structure, should there be any tendency of the same to displacement from such relation when upset. Means for this purpose may be operated in a properly timed relation to the impulsion 30 strokes of the transport means, by a lever arm 237 and connecting link 238 affixed to and oscillated by the pivot shaft 166 of said transport means. In many cases, however, means for this purpose will not be found necessary.

35 As thus far described, the machine according to this invention is adapted to automatically form packets from sheet material, and especially from metallic foil, and thereupon automatically fill the same with a desired material, and thereupon close the same. For many purposes, and especially in 40 cases wherein the packet serves merely as a commercial container for the material enclosed therein, nothing more remains to be done, and consequently the filled and closed packets may be 45 discharged from the machine upon completion of the end closure seams thereof. In other cases, other operations may be performed upon the filled and closed packets to adapt the same for some special purpose or duty. In the instant case, for 50 example, the machine according to this invention is additionally equipped with means to adapt or convert the packets, when filled with a proper material, to serve as an exothermic pad for use in hair waving or curling and similar hair dressing operations. To this end, the material with which 55 the packet is filled is of a suitable chemical nature adapted to generate heat when contacted by water or other suitable fluid. In order to give the applied water or other fluid access to the material enclosed within the packet or pad, at least one 60 wall of the latter is necessarily provided with a plurality of perforations D (see Fig. 17).

In the instant machine, the means for converting the filled packet into an exothermic pad comprises the following mechanisms, which are 65 located at stations bordering the horizontal packet runway structure to which the packets are delivered, and through which the same are moved flatwise, subsequent to the completion of the end 70 seam closures thereof. Suitably mounted in connection with the rearward frame bar 24 is a vertically oscillatable carrier frame 239, the same being oscillated in properly timed relation to the 75 intermittent movement of the filled packets through said horizontal packet runway structure

by an actuating cam member 240 which is mounted on and driven by said counter shaft 175. Said cam member 240 cooperates with the forked end plate 242 of a connecting rod 243, the upper end of the latter being operatively connected with said carrier frame 239. Carried by the carrier frame 239 are one or more downwardly facing tamper plates 244. As shown, there are three such tamper plates, disposed in alignment with successive positions of dwell of the filled packets as intermittently moved through the horizontal packet runway structure; it will be understood, however, that the number of tamper plates employed is optional, and that more or less than three thereof can be used as may be expedient. Also carried by said carrier frame 239, beyond the tamper plates, is a yieldably supported perforator head 245, the same having a desired plurality of suitably distributed downwardly projected punch elements or pins 246. In the operation of these 10 devices, as the filled packet moves step by step through the horizontal packet runway structure, and while the packets are arrested for their period of dwell, the carrier frame 239 is caused, by its actuating and timing means, to swing downward, 15 thereby carrying the tamper plates 244 into engagement with packets underlying the same, so as to tamp or press the same into a uniformly flattened condition with the content thereof firmly compacted between the walls thereof. The 20 downward swinging of the carrier frame 239 also carries down the perforator head 245 into engagement with the packet underlying the same, so that the punch elements or pins 246 are caused to 25 pierce the upwardly facing wall of said packet, to 30 thereby form the desired perforations D therein. Before the transport means again moves the 35 packets after completion of the described tamping and perforating operations, the actuating and timing means controlling the carrier frame 239 40 operates to return the same to uplifted normal initial position, ready for repetition of the above 45 described operations.

The horizontal packet runway structure terminates in a discharge chute 247, to which the completed packets or exothermic pads, as the case 50 may be, are finally delivered for discharge from the machine.

We are aware that many changes could be made in the various mechanisms and devices making up 55 the machine above described, and that many apparently widely different embodiments of the features of this invention could be made without departing from the scope thereof as defined in the following claims. It is therefore intended that 60 all matter contained in the above description or shown in the accompanying drawings shall be interpreted as illustrative and not in a limiting sense.

We claim:

1. In a machine of the kind described, in combination, a conveyer means carrying a plurality of push-plates, a table plate along which said push-plates are successively moved in operative direction by said conveyer means, means to supply sheet material across the receiving end of said table plate subject to be engaged and folded longitudinally about the push-plates as the same move onto and along said table plate and so as to provide superposed side marginal portions 65 freely projecting beyond the sides of the push-plates, folder mechanisms bordering opposite sides of said table plate adapted to engage and flatten together said superposed side marginal portions 70 of said folded sheet material and thereupon dou- 75

ble over the same inwardly upon themselves to form flat folded side closure seams, thereby converting said material into envelope-like packets open at one end, means to strip the packets from said push-plates, means to shift the packets to upstanding positions, runway means, means to transport the packets through said runway means, a packet filling mechanism bordering said runway means, and folder mechanism bordering said runway means adapted to engage the open end portions of said packets and thereupon double the same inwardly upon themselves to form and close the same by flat folded end closure seams.

2. In a machine of the kind described in combination, an intermittently actuated conveyer means having a plurality of push-plates, a table plate along which said push-plates are successively moved in operative direction by said conveyer means, timed means to feed sheet material from a supply roll thereof across the receiving end of said table plate and in the path of each push-plate as it aproaches said receiving end of said table plate, means to sever the sheet material so positioned, means to hold the sheet material subject to the severing operation and until the same is engaged by the advancing push-plate, said severed material being folded longitudinally around the free forwardly directed end of the advancing push-plate as the same moves onto and along said table plate and so as to provide superposed side marginal portions freely projecting beyond the sides of the push plates, folder mechanisms bordering opposite sides of said table plate, means to actuate said folder mechanisms in timed relation to the intermittent movement of the material carrying push-plates, said folder mechanisms being adapted to engage and flatten said superposed side marginal portions of the folded sheet material and thereupon double over the same inwardly upon themselves to form flat folded side closure seams, thereby converting said material into envelope-like packets open at one end, timed means to strip the packets from said push-plates, runway means, timed means to shift the stripped packets to upstanding position for movement through said runway means, timed means to intermittently transport the packets through said runway means, a packet filling mechanism bordering said runway means, means to actuate said filling mechanism in timed relation to the intermittent movement of the packets through said runway means, folder mechanism bordering said runway means adapted to engage the open end portions of said packets and thereupon double the same inwardly upon themselves to form and close the same by flat folded end closure seams, and means to actuate the last named folder mechanism in timed relation to the intermittent movement of the filled packets through said runway means.
3. In a machine of the kind described as defined in claim 1, including means, operative prior to discharge of the filled and closed packets from the machine, for piercing a face wall of each filled and closed packet to provide the same with a plurality of perforations.
4. In a machine of the kind described as defined in claim 2, including means operative prior to discharge of the filled and closed packets from the machine for piercing a face wall of each filled and closed packet to provide the same with a plurality of perforations, and means to actuate said perforating means in timed relation to the

intermittent movement of the filled and closed packets through said runway means.

5. In a machine of the kind described as defined in claim 1, wherein said runway means terminates in a horizontally disposed section to receive filled and closed packets flatwise therein, means to upset the filled and closed packets from upstanding to flat lying position for movement through said horizontally disposed runway section, tamping means bordering said horizontally disposed runway section to flatly compress said flat lying filled and closed packets, and means also bordering said horizontally disposed runway section, operative prior to discharge of said packets from the machine, for piercing a face wall of each filled and closed packet to provide the same with a plurality of perforations.

6. In a machine of the kind described as defined in claim 2, wherein said runway means terminates in a horizontally disposed section to accommodate filled and closed packets for flatwise movement therethrough, timed means to upset the filled and closed packets from upstanding to flat lying position for movement through said horizontally disposed runway section, tamping means bordering said horizontal runway section operative to flatly compress said flat lying filled and closed packets, means also bordering said horizontal runway section, operative prior to discharge of said packets from the machine, for piercing a face wall of each filled and closed packet to provide the same with a plurality of perforations, and means to actuate said tamping and perforating means in timed relation to the intermittent movement of the filled and closed packets through said horizontal runway section.

7. In a machine of the kind described, in combination, an intermittently actuated conveyor means having a plurality of push-plates, a table plate along which said push-plates are successively moved in operative direction by said conveyer means, means to supply sheet material across the receiving end of said table plate subject to be engaged and folded longitudinally about the push-plates as the same move onto and along said table plate and so that superposed side marginal portions of the thus folded material project freely beyond the side margins of said push-plates, fold backing rails bordering said table plate in underlying relation to said superposed side marginal portions of the material carried by said push-plates, folder mechanisms bordering opposite sides of said table plate adapted to engage and flatten down upon said fold backing rails said superposed side marginal portions of said material and thereupon double over the same inwardly upon themselves to form flat folded side closure seams, thereby converting said material into envelope-like packets open at one end, and means to actuate said folder mechanisms in timed relation to the intermittent movement of the material carrying push-plates.

8. In a machine of the kind described as defined in claim 7, including timed means to strip the formed packets from said push plates.

9. In a machine of the kind described as defined in claim 7, wherein each folder mechanism comprises an oscillatable anvil plate to determine the line of seam forming fold, an oscillatable folder arm, a folder block pivotally mounted on said folder arm, a folder blade carried by said folder block, means to yieldably position said folder block and its folder blade for initial folding effect during the initial phase of the operative movement of said folder arm, and

- means cooperative with said folder block adapted to turn the same and its folder blade for final folding effect during the final phase of the operative movement of said folder arm, said folder block cooperating with the underlying fold backing rail during performance of said final folding effect.
10. In a machine of the kind described, means for forming folded closure seams in the production of packets from sheet material comprising, an oscillatable anvil plate to determine the line of seam forming fold, an oscillatable folder arm, a folder block pivotally mounted on said folder arm, a folder blade carried by said folder block,
- 15 means to yieldably position said folder block and its folder blade for initial folding effect during the initial phase of the operative movement of said folder arm, means cooperative with said folder block adapted to turn the same and its folder blade for final folding effect during the final phase of the operative movement of said folder arm, and a stationary fold backing means with which said folder blade cooperates.
11. In a machine of the kind described, means for forming folded closure seams in the production of packets from sheet material comprising, a stationary fold backing means, an oscillatable anvil plate movable against the material supported by said fold backing means to determine
- 20 the line of seam forming fold, an oscillatable folder arm, a folder block pivotally mounted on said folder arm for turning movement relative thereto, means to yieldably position said folder block and its folder blade relative to said folder arm for initial folding effect during the initial phase of the operative movement of said folder arm, a slotted link pivotally connected with the free end portion of said folder block, a stationary stop stud engaging the slot of said link, said link being adapted to move longitudinally during the initial folding effect of said folder block and its folder blade but being arrested by said stop stud upon completion of said initial folding effect thereby to cause the turning of said folder block
- 25 and its folder blade relative to said folder arm with final folding effect during the final phase of the operative movement of said folder arm, means to actuate said folder arm, and means to actuate said anvil plate in timed relation to the movements of said folder arm.
12. In a machine of the kind described, means for forming double lapped folded closure seams in the production of packets from sheet material comprising, means to intermittently move the material operated upon, stationary fold backing means by which the portions of the material to be folded are engaged, folder mechanisms respectively stationed at different points at which the intermittently moved material dwells, the initial folding mechanism being adapted to produce a first lap fold and the succeeding folding mechanism being adapted to double said first lap fold, each said folding mechanism comprising an oscillatable anvil plate to determine a
- 30 line of fold, an oscillatable folder arm, a folder block pivotally mounted on said folder arm, a folder blade carried by said folder block, means to yieldably position said folder block and its folder blade for initial folding effect during the initial phase of the operative movement of said folder arm, and means cooperative with said folder block adapted to turn the same and its folder blade for final folding effect during the final phase of the operative movement of said folder arm.
13. In a machine of the kind described, means for forming from sheet material envelope-like packets having open mouths, comprising means to intermittently move lengths of sheet material doubled longitudinally upon itself subject to lap folding of freely projecting side marginal portions thereof to form the side closure seams of said packets, stationary fold backing means by which said side marginal portions are supported, opposed sets of folder mechanisms respectively operative upon said respective side marginal portions of the material during a period of dwell in the intermittent movement of said material, each folder mechanism including a pivotally mounted oscillatable anvil plate means to determine the line of seam forming fold, a pivotally mounted oscillatable folder arm, a folder block pivotally mounted on said folder arm, a folder blade carried by said folder block, means to yieldably position said folder block and its folder blade for initial folding effect during the initial phase of operative movement of said folder arm, means cooperative with said folder block adapted to turn the same and its folder blade for final folding effect during the final phase of operative movement of said folder arm, means for interconnecting the anvil plate means of said respective folder mechanisms for simultaneous operations, means for interconnecting the folder arms of said folder mechanisms for simultaneous operations, means to actuate said interconnected folder arms in timed relation to the dwell of the intermittently moved material, and means to actuate said interconnected anvil plate means in timed relation to the movements of said folder arms.
14. In a machine of the kind described, means for forming from sheet material envelope-like packets having open mouths, comprising means to intermittently move lengths of sheet material doubled longitudinally upon itself subject to double lap folding of freely projecting superposed side marginal portions thereof to form the side closure seams of said packets, stationary fold backing means by which said superposed side marginal portions are supported, successive opposed sets of folder mechanisms, one set of folder mechanisms being operative to produce first doubled back lap folds from said superposed side marginal portions while the succeeding set of folder mechanisms is operative to again double said first lap folds upon themselves to thereby complete the double lap side closure seams of said packets, said respective sets of folder mechanisms being respectively located relative to successive points of dwell of the intermittently moved material, and common means for actuating the successive opposed sets of folder mechanisms in timed relation to the dwell of the intermittently moved material subjected to the operation thereof.
15. In mechanism of the kind described as defined in claim 14, wherein each folder mechanism of each set thereof comprises a pivotally mounted oscillatable anvil plate means to determine the line of seam forming fold, a pivotally mounted oscillatable folder arm, a folder block pivotally mounted on said folder arm, a folder blade carried by said folder block, means to yieldably position said folder block and its folder blade for initial folding effect during the initial phase of operative movement of said folder arm, and means cooperative with said folder block adapted to turn the same and its folder blade for final

folding effect during the final phase of operative movement of said folder arm.

16. In a machine of the kind described, means for forming from sheet material envelope-like packets having open mouths, runway means, means to deliver the packets from said forming means for movement in upstanding position through said runway means, intermittently actuated means to transport said packets step by step through said runway means, and a packet filling mechanism bordering said runway means and operative at a point of dwell of the packets intermittently moved through the latter, said filling mechanism comprising a filling substance supply hopper having a rotatable discharge valve means at its lower end, a vertically reciprocable funnel means below said discharge valve, said funnel means having a tapered free end provided in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means in timed relation to the dwell of the packets as intermittently moved in said runway means, and means to actuate said discharge valve in timed relation to the movements of said funnel means.

17. In a machine of the kind described, means for forming from sheet material envelope-like packets having open mouths, runway means, means to deliver the packets from said forming means for movement in upstanding position through said runway means, intermittently actuated means to transport said packets step by step through said runway means, a packet filling mechanism bordering said runway means and operative at a point of dwell of the packets intermittently moved through the latter, a packet closing means also bordering said runway beyond said filling mechanism, said filling mechanism comprising a filling substance supply hopper having a rotatable discharge valve means at its lower end, a vertically reciprocable funnel means below said discharge valve, said funnel means having a tapered free end provided in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means in timed relation to the dwell of the packets as intermittently moved in said runway means, and means to actuate said discharge valve in timed relation to the movements of said funnel means.

18. In a machine of the kind described, means for forming from sheet material envelope-like packets having open mouths, runway means, means to deliver the packets from said forming means for movement in upstanding position through said runway means, intermittently actuated means to transport said packets step by step through said runway means, and a packet filling mechanism bordering said runway means and operative at a point of dwell of the packets intermittently moved through the latter, said filling mechanism comprising a filling substance supply hopper having a throat housing at its lower end provided with an upper intake opening and lower discharge opening, said throat housing having a transverse bore intermediate its intake and discharge openings, a valve member rotatable in

said bore, said valve member having a series of successive substance conveying pockets in its periphery, a vertically reciprocable funnel means below said throat housing discharge opening, said funnel means having a tapered free end provided in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means in timed relation to the dwell of the packets as intermittently moved in said runway means, and means to actuate said discharge valve in timed relation to the movements of said funnel means.

19. In a machine of the kind described, means for forming from sheet material envelope-like packets having open mouths, runway means, means to deliver the packets from said forming means for movement in upstanding position through said runway means, intermittently actuated means to transport said packets step by step through said runway means, a packet filling mechanism bordering said runway means and operative at a point of dwell of the packets intermittently moved through the latter, a packet closing means also bordering said runway beyond said filling mechanism, said filling mechanism comprising a filling substance supply hopper having a throat housing at its lower end provided with an upper intake opening and lower discharge opening, said throat housing having a transverse bore intermediate its intake and discharge openings, a valve member rotatable in said bore, said valve member having a series of successive substance conveying pockets in its periphery, a vertically reciprocable funnel means below said throat housing discharge opening, said funnel means having a tapered free end provided in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means in timed relation to the dwell of the packets as intermittently moved in said runway means, and means to actuate said discharge valve in timed relation to the movements of said funnel means.

20. In a machine of the kind described, means for forming from sheet material envelope-like packets having open mouths, runway means, means to deliver the packets from said forming means for movement in upstanding position through said runway means, intermittently actuated means to transport said packets step by step through said runway means, and a packet filling mechanism bordering said runway means and operative at a point of dwell of the packets intermittently moved through the latter, said filling mechanism comprising a filling substance supply hopper having a throat housing at its lower end provided with an upper intake opening and lower discharge opening, said throat housing having a transverse bore intermediate its intake and discharge openings, a valve member rotatable in said bore, said valve member having a series of successive substance conveying pockets in its periphery, a vertically reciprocable funnel means below said throat housing discharge opening, said funnel means having a tapered free end provided

in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means in timed relation to the dwell of the packets as intermittently moved in said runway means, said latter means including a control cam, said cam having auxiliary agitator cam portions adapted to vertically vibrate said funnel means when operatively entered into a packet, and means to actuate said discharge valve in timed relation to the movements of said funnel means.

21. In a machine as defined in claim 1, wherein said filling mechanism comprises, a filling substance supply hopper having rotatable discharge valve means at its lower end, said valve means having a series of successive substance conveying pockets in its periphery, a vertically reciprocable funnel means into which said valve means discharges, said funnel means having a tapered free end provided in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means including a control cam, said cam having auxiliary agitator cam portions adapted to vertically vibrate said funnel means when operatively entered into a packet, and means to actuate said discharge valve in timed relation to the movements of said funnel means.

22. In a machine as defined in claim 2, wherein said filling mechanism comprises, a filling substance supply hopper having rotatable discharge valve means at its lower end, said valve means having a series of successive substance conveying pockets in its periphery, a vertically reciprocable funnel means into which said valve means discharges, said funnel means having a tapered free end provided in part by a pivoted gate member, said tapered free end upon descent of said funnel means being adapted to enter the mouth of a packet dwelling in said runway means below said hopper, means to open said gate member to expand the packet mouth upon entrance of said funnel means into the latter, means to reciprocate said funnel means including a control cam, said cam having auxiliary agitator cam portions adapted to vertically vibrate said funnel means when operatively entered into a packet, and means to actuate said discharge valve in timed

relation to the movements of said funnel means.

23. In a machine of the kind described, means for forming from sheet metal envelope-like packets having open mouths, runway means, means to deliver the packets from said forming means for movement in upstanding position through said runway means, intermittently actuated means to transport said packets step by step through said runway means, a packet filling mechanism bordering said runway means and operative at a point of dwell of the packets intermittently moved through the latter, a packet closing means also bordering said runway means beyond said filling mechanism, and means also bordering said runway means beyond said packet closing means for piercing a face wall of each filled and closed packet to provide the same with a plurality of perforations.

24. In a machine of the kind described, means for forming from sheet metal envelope-like packets having open mouths, runway means, means to deliver the packets from said forming means for movement in upstanding position through said runway means, intermittently actuated means to transport said packets step by step through said runway means, a packet filling mechanism bordering said runway means and operative at a point of dwell of the packets intermittently moved through the latter, a packet closing means also bordering said runway means beyond said filling mechanism, means beyond said packet closing means for flatly compressing the filled and closed packets, and means beyond said compressing means for piercing a face wall of each filled and closed packet to provide the same with a plurality of perforations.

25. In a machine of the kind described, a conveyor means carrying a plurality of push-plates, a table plate along which said push plates are successively moved in operative direction by said conveyor means, means to supply sheet material across the receiving end of said table plate subject to be engaged and folded longitudinally about the push-plates as the same move onto and along said table plate and so as to provide superposed side marginal portions freely projecting beyond the sides of the push-plates, and folder mechanisms bordering opposite sides of said table plate adapted to engage and flatten together said superposed side marginal portions of said folded sheet material and thereupon double over the same inwardly upon themselves to form flat folded side closure seams, thereby converting said material into envelope-like packets open at one end.
